UNITED STATES PATENT OFFICE.

ALBERT S. COX, OF GRANTWOOD, NEW JERSEY.

MILITARY UNIFORM OR THE LIKE.

1,139,642.

Specification of Letters Patent. Patented May 18, 1915.

Application filed October 17, 1913. Serial No. 795,620. Renewed March 3, 1915. Serial No. 11,875.

To all whom it may concern:

Be it known that I, ALBERT S. Cox, a citizen of the United States, residing at Grantwood, New Jersey, have invented certain new and useful Improvements in Military Uniforms or the like, of which the following is a clear, full, and exact description.

My invention relates to apparel and articles particularly adapted for military uniforms and equipment such as blankets, arms, tents, etc., and my object is to render the same less easily distinguished by the eye particularly when viewed against a background of natural foliage and the like.

The drawing, which shows a military blouse and trousers, discloses one embodiment of my invention.

In this preferred embodiment the portions represented by the cross-hatched lines, such as 1, are of a relatively dark color such as what is now known as military olive drab. The light or unshaded portions 2 are of a relatively lighter shade such as a light greenish yellow. It will be observed that the two colors are arranged in what might be termed up and down stripes, although these stripes are very irregular in position and outline. The continuity of the stripes is broken at irregular intervals by transverse portions of the contrasting color, as for example shown at 3, 3. The outlines of the portions are also preferably irregular or wavy in appearance as shown. I also prefer to give a representation of "depth" by making the outline between the light and dark portions, or some of them, of a darker color than even the olive drab, and preferably black or nearly so, as shown by the heavy black outline at 4, for example. I also prefer to break up any possible uniformity by isolated patches of one color irregularly disposed on the contrasting color such as for example as shown at 5 and 6. Some of these may have dark outlines as indicated at 6 and 7, and others may be without the dark outlines as for example at 8 and 9. The spots are also of irregular sizes as shown. I also prefer to still further break up the uniformity by transverse strokes or patches of a still different color such as indicated at 10, which I prefer to make of light gray. The outline or appearance may be still further destroyed by adding to the uniform irregular portions such as 11 in the form of leaves.

By actual test I have found that a uniform embodying my invention as above described is almost invisible even a short distance away when against a natural background such as grass, foliage or the like.

I am aware that my invention may be embodied in various forms and it is not limited to a military uniform as it may be employed for a hunter's clothing. I therefore do not desire to be limited to the above illustrated embodiment of my invention.

What I claim as new is:

1. A military uniform or the like, having irregularly disposed stripes up and down of dark and relatively light colors with irregular wavy outlines, the continuity of the stripes of one color being broken at irregular intervals by transverse irregular portions of the other color.

2. A military uniform or the like, having irregularly disposed stripes up and down of substantially army olive drab and light greenish yellow colors with irregular wavy outlines, the continuity of the stripes of one color being broken at irregular intervals by transverse irregular portions of the other color.

3. A military uniform or the like, having irregularly disposed stripes up and down of dark and relatively light colors with irregular wavy outlines, the continuity of the stripes of one color being broken at irregular intervals by transverse irregular portions of the other color, and isolated patches of one color superposed on the other.

4. A military uniform or the like, having irregularly disposed stripes up and down of dark and relatively light colors with irregular wavy outlines, the continuity of the stripes of one color being broken at irregular intervals by transverse irregular portions of the other color, some of the colors being outlined by still darker colors.

5. An article of the character described rendered less easily visible by pronounced irregular alternating patches of contrasting light and dark colors with wavy outlines, some of the darker patches being outlined in a still darker color, the color effect of some of said patches being broken up by smaller spots of contrasting color and all producing the effect of uncertain light and shade.

6. A military article of the character described having interrupted, alternating, irregular, elongated areas of contrasting light

and dark colors, some of said areas being outlined in contrasting colors thereby producing the effect of uncertain light and shade and rendering the article visible with difficulty at certain ranges.

7. A military uniform having interrupted, alternating, irregular areas of contrasting light and dark colors, some of said areas being outlined in darker color and thereby producing the effect of uncertain light and

shade and rendering the uniform distinguishable with difficulty at certain ranges substantially as described.

Signed at New York city, N. Y. this 16th day of October, 1913.

ALBERT S. COX.
